UNITED STATES PATENT OFFICE.

JOHN F. GAIL, OF EVANSTON, ILLINOIS, ASSIGNOR TO SIMMONS COMPANY, OF NEW YORK, N. Y., A CORPORATION OF DELAWARE.

METAL-PRINTING MACHINE.

Application filed July 6, 1926. Serial No. 120,560.

This invention relates to machines for applying to metal surfaces a coating of suitably colored ink or paint in imitation of wood surface, so as to produce a wood grain appearance or effect. This practice is at 5 present extensively followed in the manufacture of metal bedsteads and other articles of bedroom furniture.

The machine of the present invention employs 10 a pair of pattern rollers, the peripheral surfaces of which are engraved by an etching process to carry, in intaglio, the design to be printed, and these engraved surfaces, coated with ink, are impressed in rolling contact 15 into the soft peripheries of a pair of gelatine covered printing rollers, to which latter the ink, retaining the design on the pattern rollers, is bodily transferred; and the bar, rod or sheet of metal to be decorated 20 is then run between the said printing rollers, by which latter the ink, in the same design, is transferred to the opposite surfaces of said bar, rod or sheet.

In such a machine the roller surfaces from 25 and to which the ink is transferred must operate in absolute rolling contact with each other, since the slightest amount of sliding contact will smear the ink and wreck the design. Furthermore, to effect the transfer 30 of the ink from the pattern roller to the printing roller, the peripheries of the two rollers must operate not in line contact with each other, but the periphery of the pattern roller must operate in depressing surface 35 contact with the soft periphery of the printing roller through an appreciable arc. I have found that this compression does not reduce the effective radius of the printing roller, but on the contrary, has the effect of 40 slightly stretching, and thus lengthening, the periphery of the printing roller thereby increasing its effective radius. Thus it follows that the speeds of the two rollers cannot be in exact inverse ratio to the radii of 45 their absolute peripheries, but the speed of the printing roller must be slightly retarded relatively to the speed it would have if the rollers operated in line contact, in order to insure perfect rolling contact and freedom 50 from smear. One object of the present invention is to produce a machine of the character and type specified wherein this

speed relation between the pattern and printing rollers shall be attained.

Furthermore, in such a machine, if the 55 pattern roller is allowed to remain idle in depressing contact with the gelatine printing roller for more than a short period of time it produces a permanent depression or dent in the periphery of the latter roller; 60 and hence, when the operation of the machine is intermittent, the two rollers should be separated at least to the extent of relieving the printing roller from the depressing contact of the pattern roller and allowing its 65 depressed portion to re-expand to the line of its absolute periphery. Another object of the instant invention is to provide improved means for effecting this separation of the rollers when the machine is idle. Preferably, and in the form of the invention herein presented, this roller separating means is connected to a control member of the power that operates the machine, as, for example, to the starting and stopping switch of an 75 electric motor, so that when the power is thrown off, the separation of the rollers occurs simultaneously therewith.

Again, both the pattern rollers and the printing rollers are equipped with suitable 80 wipers to remove surplus ink therefrom; and when the machine is idle it is desirable that these wipers also be moved out of contact with the rollers to avoid the deposit of dried ink marks or lines thereon by the contacting 85 portions of the wipers which might mar the subsequent work of the machine. A further object of the invention, therefore, is to provide, in a machine of the character specified, improved roller wipers, with means for re- 90 tracting the same from the surfaces of the rollers when the machine is stopped; said retracting means being preferably connected and coordinated with the roller separating 95 means so as to operate simultaneously with the latter.

Other objects and attendant advantages of the invention will be apparent to persons skilled in the art as the same becomes better understood by reference to the following 100 detailed description, taken in connection with the accompanying drawings wherein I have illustrated one practical embodiment of the invention, and in which—

- Fig. 1 is a front elevation of the machine;
 Fig. 2 is a side elevation, viewed from the right of Fig. 1;
 Fig. 3 is a vertical section on the line 3—3 of Fig. 2;
 Fig. 4 is a detail view of part of the scraper actuating mechanism;
 Fig. 5 is a detail side elevation of the motor switch-box and switch-actuating arm and link;
 Fig. 6 is a top view as seen on the line 6—6 of Fig. 1;
 Fig. 7 is an enlarged section through the printing rolls and their bearings on the line 15 7—7 of Fig. 1; and
 Fig. 8 is an enlarged sectional detail through the meeting portions of the peripheries of the pattern and printing rollers, taken on the line 8—8 of Fig. 1.
- 20 Referring to the drawings, 10 designates a base on which are mounted a pair of spaced vertical front and rear frame members 11 and 12 respectively. 13 designates a drive shaft journaled horizontally in bearings in the frame members 11, 12, and having mounted on one end thereof which projects forwardly of the frame 11 a gelatine-covered printing roller 14. Journaled in bearings in the frame members 11 and 12 above and parallel with 25 the drive shaft 13 is a shaft 15 carrying on its overhanging end a similar printing roller 16. Fast on the drive shaft 13 is a spur gear 17 (Fig. 3) driving a spur gear 18 of equal diameter and number of teeth fast on the shaft 15, whereby the two printing rollers 14 and 16 are rotated in opposite directions at 30 equal speeds.
- 19 and 20 designate a pair of fixed pivot shafts mounted in and between the frame members 11 and 12. Pivoted on the shaft 19 is a yoke 21, most clearly shown in Fig. 6; and journaled in bearings in the opposite sides of the yoke 21 is a shaft 22, fast on one overhanging end of which is a pattern roller 24. The periphery of this roller, as shown in the detail view Fig. 8, is equipped with a thin band 25 of copper or other suitable metal, in the surface of which is engraved by etching or otherwise a wood grain pattern. The periphery of this pattern roller is in rolling engagement with the periphery of the printing roller 16, as clearly shown in Fig. 1.
- 55 Pivoted on the shaft 20 is a similar yoke 26, in the opposite arms of which is journaled a shaft 27 carrying on its overhanging end a pattern roller 28 similar to the pattern roller 24, having its periphery normally in rolling contact with the periphery of the printing roller 14, as clearly shown in Fig. 1.
- 60 Fast on shaft 22 is a gear 29 meshing with and driven by a gear 30 fast on the shaft 15; and fast on the shaft 27 is a gear 31 meshing with and driven by a gear 32 fast on the drive shaft 13. The gears 29 and 31 are of equal 65 diameters and equal numbers of teeth, and the same is true of the gears 30 and 32, so that the two pattern rollers 24 and 28 are rotated in opposite directions at equal speeds.
- 33 and 34 (Fig. 1) designate a pair of ink pans mounted on the frame member 11, into which dip inking rollers 35 and 36 that serve the pattern rollers 24 and 28 respectively. Inking roller 35 is fast on a shaft 37 journaled in bearings in a pair of arms 38 formed on the yoke 21 below the pivot of the latter, and said shaft is rotated by a gear 39 fast thereon meshing with and driven by the gear 29. Inking roller 36 is fast on a shaft 40 journaled in arms 41 on the yoke 26 slightly above the pivot of the latter, said shaft being driven by a gear 42 fast thereon meshing with and driven by the gear 31.
- When the machine is operating the yokes 21 and 26 are respectively swung downwardly and upwardly a slight distance which 85 forces the peripheries of the pattern rollers 24, 28 into the soft peripheries of the printing rollers 16 and 14. When, however, the operation of the machine is intermittent, it is essential to relieve the pressure of the pattern rollers on the printing rollers and this is done by bodily shifting the pattern rollers away from the printing rollers sufficiently to permit the impressed or indented portions of the printing rollers to re-expand into the normal peripheral surfaces thereof. In Fig. 3 is illustrated a simple pedal-actuated mechanism for doing this. Referring thereto, 43 is a rock shaft mounted in and between the frame members 11 and 12. Fast on this rock shaft 90 is a rocking beam 44, to one arm of which is pivoted a long upwardly extending link 45, the upper end of which is pivoted to one arm 46 of a lever that is pivoted at 47 in a bracket 48, see Fig. 6, attached to the upper end of the frame member 11. The other arm 49 of said lever is connected by a short link 50 to the transverse limb of the yoke 21. From this it will be seen that the rocking of the shaft 43 in a direction to draw the link 45 downwardly 95 will effect a slight lifting movement of the yoke 21 just sufficient to remove the pattern roller 24 from depressing engagement with the printing roller 16. This movement is so slight, however, that it does not separate the gears 29 and 30.
- To the other arm of the rocking beam 44 is pivotally connected an upwardly extending link 51 pivotally connected at its upper end to the long arm 52 of a lever that is pivoted at 53 to a bracket 54 (Fig. 2) attached to the frame member 11, the short arm 55 of said lever being connected by a short link 56 to the transverse member of the yoke 26; from which it will be seen that when the rock shaft 43 is turned in a direction to draw down the link 45 and simultaneously raise the link 51, the yoke 26 will be swung downwardly sufficiently to withdraw the periphery 100 of the pattern roll 28 from depressing con-
- 115 120 125 130

tact with its co-operating printing roll 14, this occurring without separating the transmission gears 31 and 32.

Fig. 7 illustrates the preferred construction and mounting of the printing rollers 14 and 16. As herein shown each roller comprises an axially bored spool 57 mounted fast on its operating shaft by an expansion bolt 58 co-operating with wedge blocks 59 which are expanded by the head of the wedge bolt into clutch engagement with the bores of the spools, and a thick peripheral ring 60 of a gelatine composition that is soft and slightly resilient. In order to permit a limited variation in the spacing of the printing rolls, the shaft of one of them (shaft 15 as herein shown) is journaled in eccentric bearings 61, these latter being rotatably mounted in bearing bosses 62 on the upright frame members 11 and 12. These bearings are connected for simultaneous rocking movement by a U-shaped bail 63, the horizontal limb of which may be swung upwardly or downwardly to effect the desired spacing of the printing rollers. 64 designates each of a pair of angle brackets attached to the frame member 11, between which is journaled a horizontal guide and gage roller 65 adapted to bear against the rear side or edge of the work as the latter is passed between the printing rollers. The teeth of the gears 18 and 30 on the shaft 15 are made long enough to remain in mesh with the teeth of their co-operating gears under the described adjustments of the shaft 15.

Journalized in the frame plate 11 between the printing roller 16 and the inking roller 35 are a pair of wiper shafts 66, 67. Secured on an overhanging end of shaft 66 is a wiper in the form of a scraper blade 68 that co-operates with the periphery of the pattern roller 24, and fixed on the corresponding overhanging end of shaft 67 is a scraper blade 69 that co-operates with the periphery of the printing roller 16. Also journalized in the frame plate 11 at suitable points are similar wiper shafts 70 and 71. On an overhanging end of shaft 70 is a scraper blade 72 co-operating with the periphery of the pattern roller 28, and on the corresponding overhanging end of the shaft 71 is a scraper blade 73 co-operating with the periphery of the printing roller 14. The working edges of all of the scraper blades are lightly held in trailing contact with their respective rollers by spring-actuated mechanism, as follows.

Referring to Fig. 3, fast on shaft 67 is a depending arm 74 to which is connected a pull spring 75 that is anchored at 76 to the frame 11. Fast on the shaft 66 and loose on shaft 67 outside the frame member 11 are a pair of collars 77 and 78 respectively (Fig. 4) connected for simultaneous rocking movement in opposite directions by a knuckle joint 79. The collar 78 is angularly adjustable on shaft 67 by a lateral lug 80 thereon lying between a

pair of adjusting screws 81 mounted in a fork 82 fast on shaft 67. By this mechanism the working edges of the two scraper blades 69, 68 are lightly held in trailing engagement with the peripheries of their respective rollers, with capacity of relative adjustment through screws 81. Fast on link 45 is a collar 83 that, in the normal high position of the link 45, lies above and in contact with an arm 84 fast on the scraper shaft 67. When link 45 is depressed, the two shafts 67 and 66 are rocked by the arm 84 and their jointed connection in directions to simultaneously swing the working edges of the scraper blades away from their respective rollers against the pull of spring 75. The free end of arm 84 is connected by a link 85 to the plunger of a dash pot 86 attached to the inner side of the frame member 11; the plunger of the dash pot moving freely downward but having a retarded upward movement, so as to effect the slow and gradual return of the scraper blades to working position under the pull of spring 75.

A similar mechanism is employed to effect the actuating and control of the scraper blades 72 and 73, including an arm 74' fast on shaft 71, a pull spring 75', and a jointed connection between the shafts 70 and 71 similar to that above described and shown in Fig. 4, but located inside the frame member 11. An arm 84' fast on shaft 7 is connected by a link 85' to the plunger of a dash pot 86' attached to the inner side of the frame member 11; the plunger of this dash pot moving freely upward but having a retarded downward movement to effect the slow and gradual return of the scraper blades 72 and 73 to working position under the pull of spring 75'. Fast on link 51 is a collar 83' that, in the normal low position of the link 51, lies beneath and in contact with the arm 84', so that, when link 51 is raised, the two shafts 70 and 71 are rocked by the arm 84' and their jointed connection in directions to simultaneously swing the working edges of the scraper blades away from their respective rollers.

Fig. 3 shows the normal positions of the rocking beam 44, the links 45 and 51 and the parts operated by the latter when the machine is in working position. The rocking of the shaft 43 to separate the pattern and printing rollers and retract the scraper blades from said rollers is preferably effected by a pedal mechanism, as follows.

Mounted on a pivot stud 87 in the frame member 11 is a two-arm pedal lever 88 formed with pedals 89 and 90 at the ends thereof. Attached to the pedal lever 88 over the pivot stud 87 is an upwardly extending cam plate 91 formed with a cam slot 92, which is engaged by a roller 93 (Fig. 1) on a pin 94 mounted in the free end of an arm 95 fast on the rock shaft 43. A pull spring 96 anchored at 97 to the base plate 10 and at its

other end connected to a pin 98 in the top of the cam plate 91 is adapted to oscillate across the pivot 87 of the foot lever 88 and thus hold the latter in either extreme of its 5 rocking movement. Depression of the pedal 89, as shown in Figs. 1 and 3, raises the link 45 and lowers the link 51, placing the rollers and scrapers in the working position shown in Fig. 1. Depression of the pedal 90, through 10 the cam 92, cam follower 93, arm 95 and rock shaft 43 lowers the link 45, raises the link 51, separates the pattern and printing rollers and retracts the scrapers from engagement with their respective rollers.

15 As herein shown, power is applied to the drive shaft 13 through a worm gear 100 (Fig. 2) fast thereon driven by worm 101 on the shaft of an electric motor 102 mounted on a bracket 103 on the rear of the frame plate 12. 20 Also mounted on said frame plate beneath the motor are a starting controller conventionally indicated at 104 and a switch box conventionally indicated at 105. Preferably the starting and stopping switch in the switch 25 box 105 is connected to the rock shaft 43 so that when the latter is rocked by the pedal lever in a direction to throw the rollers and scrapers into working position the motor switch is closed, and vice versa. A simple 30 connection for this purpose is indicated in Figs. 2 and 5 as comprising an arm 106 fast on the rock shaft 43 and a link 107 connecting said arm to the switch-opening and closing rod 108 of the switch box.

35 In operating the machine, the pedal 89 is depressed which moves the rollers and scrapers into working relation and simultaneously closes the motor switch, starting the machine in operation. The rod, bar or 40 sheet of metal to be decorated is then passed by the operative between the printing rollers 14 and 16 from right to lift viewing Fig. 1 at a linear speed substantially equal to the peripheral speed of the two rollers, the latter 45 turning in the direction indicated by the arrows. The spacing of the printing rollers for any given job is slightly less than the thickness of the work, so that the gelatinous peripheries of the rollers are impressed on 50 the surfaces of the work and transfer the ink to the latter in the grain or other design received from the pattern rollers. When the job is done, the operative depresses pedal 90, which opens the motor switch and simultaneously 55 shifts the pattern rollers and the scrapers out of contact with the printing rollers.

Since, as before stated, in order to transfer a perfect impression of the design from 60 the pattern rollers to the printing rollers through rolling surface contact, the speed of the printing rollers must be slightly less than it would be if the pattern and printing rollers operated in rolling line contact, I secure this 65 result by giving to the gears 29 and 30 a

slightly different ratio from that of the rollers 24 and 16, and by giving to the gears 31 and 32 a correspondingly different ratio from that of the rollers 28 and 14, such as will cause the printing rollers 16 and 14 to rotate 70 at a slightly slower speed than they would if the ratios of the rollers and their respective gears were exactly the same. This, as stated, avoids sliding or rubbing contact of the co-operating peripheries of the rollers, while 75 permitting the pattern rollers to operate in depressing surface contact with the printing rollers so as to efficiently transfer the ink in the selected pattern or design to the latter.

I have herein shown and described, for purposes of illustration, one simple and practical embodiment of the principle of the invention, but manifestly the details of structure and arrangement may be widely varied from those shown without involving any departure from the mechanical principles involved or sacrificing any of the utilities and advantages of the invention. Hence, I do not limit the invention to the particular embodiment illustrated, but reserve all such variations, modifications and mechanical equivalents as fall within the spirit and purview of the claims.

I claim—

1. In a metal printing machine, the combination of a printing roller formed with a soft peripheral surface, a pattern roller having its peripheral surface in depressing rolling contact with the periphery of said printing roller, an inking roller co-operating with said pattern roller, a pair of scrapers respectively engaging the peripheries of said printing and pattern rollers, and means for simultaneously separating said printing and pattern rollers and moving said scrapers out of contact with their respective rollers when the machine is idle.

2. In a metal printing machine, the combination of a frame, a printing roller journaled in said frame, a yoke pivoted in said frame, a shaft journaled in and between the arms of said yoke, a pattern roller fast on said shaft with its periphery in rolling contact with said printing roller, means for driving both said rollers, and means for swinging said yoke whereby to shift said pattern roller into and out of contact with said printing roller.

3. In a metal printing machine, the combination of a frame, a pair of peripherally spaced printing rollers between which the work is adapted to be passed journaled in said frame, a pair of yokes pivoted in said frame, shafts journaled in and between the arms of said yokes respectively, pattern rollers fast on said shafts with their peripheries in rolling contact with said printing rollers, means for driving said printing and pattern rollers, and means for simultaneously swinging said yokes in the same direction relatively to said printing rollers whereby to shift said pattern

rollers into and out of contact with said printing rollers.

4. A specific embodiment of claim 3, wherein in the means for swinging said yokes includes 5 a rock shaft journaled in the frame, a rocking beam fast on said rock shaft, levers pivoted on said frame and connected to said yokes, and links connecting said levers to the ends of said rocking beam.
- 10 5. A specific embodiment of claim 3, wherein in the means for swinging said yokes comprises a rock shaft journaled in the frame, a rocking beam fast on said rock shaft, levers pivoted on said frame and connected to said 15 yokes, links connecting said levers to the ends of said rocking beam, a pedal lever pivoted on said frame, actuating connections from said pedal lever to said rock shaft, and a spring operative to hold said pedal lever in either set 20 position.
6. In a metal printing machine, the combination of a frame, pattern and printing rollers journaled in said frame with their peripheries in rolling contact, an inking roller co-operating with said pattern roller, a pair 25 of scraper shafts journaled in said frame, scraper blades mounted on said shafts and co-operating with said pattern and printing rollers respectively, transmission mechanism connecting said shafts, spring-actuated means 30 connected to one of said shafts for swinging said scraper blades into contact with their respective rollers, an arm on one of said shafts, and means acting on said arm and through said transmission mechanism to simultaneously 35 retract both of said scraper blades from said rollers.
7. In a metal printing machine, the combination of a frame, pattern and printing rollers journaled in said frame with their peripheries in rolling contact, an inking roller co-operating with said pattern roller, an electric motor and transmission mechanism therefrom to said rollers, a switch controlling the motor circuit, means for moving one of said 40 rollers bodily into and out of contact with the other, and means connected to said roller-moving means operative to close said switch when said rollers are brought into contact and to open said switch when said rollers are 45 separated.

JOHN F. GAIL.
